UNITED STATES PATENT OFFICE.

HENRY C. LENDERMAN, OF PORTLAND, OREGON.

SLIDE-VALVE.

SPECIFICATION forming part of Letters Patent No. 778,419, dated December 27, 1904.

Application filed August 12, 1904. Serial No. 220,546.

To all whom it may concern:

Be it known that I, HENRY C. LENDERMAN, a citizen of the United States, residing at Portland, in the county of Multnomah and State of Oregon, have invented certain new and useful Improvements in Slide-Valves; and I do hereby declare the following to be a full, clear, and exact description of the invention, such as will enable others skilled in the art to which it applies to make and use the same.

This invention relates to the slide-valves used for distributing steam to the cylinders of steam-engines; and it consists in the novel construction and combination of the parts hereinafter fully described and claimed.

In the drawings, Figure 1 is a longitudinal section through a steam-chest and a slide-valve constructed according to this invention. Fig. 2 is a plan view of the face of the slide-valve.

A is a portion of a steam-cylinder, and b represents its steam-supply ports at the ends thereof.

B represents the exhaust-cavities, and C is the steam-inlet cavity, which receives the steam from a suitable supply-pipe.

D is the slide-valve, which is of the type shown in the patent to C. M. Giddings, dated March 17, 1885, No. 314,120. This slide-valve is provided with a cover 2, two curved diaphragms 3, having steam-supply ports 4 in them, and exhaust-chambers 5 at the inner faces of the diaphragms. The diaphragms are arranged near the ends of the valve, and E is a steam-space between them. Ports or passages for steam e extend over the diaphragms to the face of the valve. F is the steam-chest, in which the said slide-valve works, and f is the valve-rod by means of which the said valve is reciprocated in the steam-chest. The steam from the boiler enters the steam-cavity C under the valve, and the steam-space E and the ports e are always filled with steam at the full working pressure. The steam is admitted to the ends of the cylinder by the ports 4 and is exhausted by means of the exhaust-chambers 5.

In operating slide-valves of this construction trouble is frequently occasioned by the breaking of the valve-spindles, because of the

imperfect balancing of the slide-valves. In order to overcome this difficulty, two valves G and I are provided and are secured to the cover 2 inside the steam-space E of the valve between the two diaphragms 3. The valve G is an inlet-valve, which admits the steam from the steam-space E to the space 6 behind the valve inside the steam-chest. The valve G is arranged in a valve-casing g, which is provided with a suitable seat for the valve. The valve G is normally held to its seat by a light spring h, and H is a screw working in a suitable nut and operating to regulate the pressure of the spring and also to guide the valve-spindle. The valve I is arranged in a valve-casing i, which is provided with a suitable seat for the valve. This valve I is a relief-valve which admits steam from the space 6 behind the valve to the steam-space E inside the valve when the pressure in the said space 6 exceeds that in the steam-space E. The valve I is normally held to its seat by the pressure of the steam inside the steam-space E. The two valve-casings depend from the said valve-cover between the said diaphragms of the valve and travel back and forth with the said valve.

What I claim is—

1. The combination, with a steam-chest, and a slide-valve working therein and provided with an internal steam-space and diaphragms at its end portions which form steam-ports and exhaust-chambers; of two valves G and I which open in opposite directions, said valves being suspended from the cover 2 of the said slide-valve in the steam-space between its said diaphragms and operating to maintain the steam-pressure in the said steam-space of the valve and in the steam-chest behind the valve at a prearranged ratio.

2. The combination, with a steam-chest, and a slide-valve working therein and provided with an internal steam-space and diaphragms at its end portions which form steam-ports and exhaust-chambers; of a valve carried by the said valve and operating to admit steam from the steam-chest to the said steam-space inside the valve whenever the pressure in the steam-chest exceeds that in the said steam-space, and a second valve also carried by the

said slide-valve and provided with an adjustable spring and means for adjusting the pressure of the said spring and operating to admit steam from the said steam-space inside the valve to the said steam-chest when the pressure in the said steam-space exceeds that in the said steam-chest by a prearranged amount.

3. The combination, with a steam-chest, and a slide-valve working therein and provided with an internal steam-space and distributing-ports; of two valves G and I which open in

opposite directions, said valves being carried by the said slide-valve and operating normally to maintain a lower pressure in the steam-chest than in the said steam-space and to prevent the pressure in the valve-chest from exceeding that in the said steam-space. 15

In testimony whereof I have affixed my signature in the presence of two witnesses.

HENRY C. LENDERMAN.
